UNITED STATES PATENT OFFICE.

ROGER SHERMAN HOAR, OF CONCORD, MASSACHUSETTS, ASSIGNOR TO JOHN W. WEEKS, SECRETARY OF WAR OF THE UNITED STATES OF AMERICA, TRUSTEE.

MEANS FOR AND METHOD OF DETERMINING TRUE NORTH, LATITUDE, AND APPROXIMATE SIDERAL TIME, OR ANY OF THEM.

Application filed May 21, 1919. Serial No. 298,605.

(FILED UNDER THE ACT OF MARCH 3, 1883, 22 STAT. L., 625.)

To all whom it may concern:

Be it known that I, ROGER SHERMAN HOAR, a citizen of the United States, and a resident of Concord, in the county of Middlesex and State of Massachusetts, have invented an Improvement in Means for and Methods of Determining True North, Latitude, and Approximate Sideral Time, or Any of Them, of which the following description, in connection with the accompanying drawings, is a specification, like characters on the drawings representing like parts.

The invention described herein may be used by the Government or any of its officers or employees in prosecution of work for the Government, or by any other person in the United States without payment to me of any royalty thereon in accordance with the act of March 3, 1883.

This invention relates to means for and method of determining true north, and more particularly it relates to a so-called Polaris attachment which may be used with an ordinary surveyor's transit or like sighting instrument to determine the true north in the field, at any hour of the night, without reference to books or tables, with the necessity for only one setting of the transit or other instrument, and without the necessity of knowing either the latitude or the time, even approximately.

In order that the principle of my invention may be readily understood, I shall describe one embodiment thereof and the best mode known to me for practising the method.

In the accompanying drawings:

Fig. 1 is a perspective view of a transit having applied thereto one embodiment of my invention herein constituting an attachment or accessory therefor;

Fig. 2 is a plan view of the said attachment and whereon I have indicated the plane of sight and also a line parallel to the so-called straight-edge;

Fig. 3 is a vertical section taken through the tube of the attachment and representing the prisms supported therein but not showing the so-called straight-edge;

Fig. 4 is a detail in side elevation of the interior of the tube and showing adjusting means for said prisms;

Fig. 5 is a transverse section upon the line 5—5 of Fig. 4; and

Fig. 6 represents the astronomical triangle.

Fig. 7 is a vertical section through a modified form of the attachment; and

Fig. 8 is a perspective of one of the prism rings, the other ring being a duplicate thereof.

The general principle of my invention is a mechanical means for north-determination by the so-called hour angle method, the hour angle or sideral time being set by lining up an element of the invention on two stars.

In its simplest embodiment, to which, however, it is not restricted, my invention is a simple accessory for an ordinary surveyor's transit or like instrument. Obviously it has a wide application of use. One extensive field of use is for orientation for heavy artillery, and by means of the invention the result obtained will be within the allowable error of precision for artillery work. North-determination by means of my invention in its simplest embodiment is purely a field method, no computations or even interpolations being involved. The same setting which gives the azimuth of the reference-line also gives the latitude and may be made to give the approximate sidereal time simply by graduating the cylinder of the attachment.

Before describing the illustrated form of the apparatus or means of my invention by detailed reference to the drawing, I will briefly describe the same with general reference to its mode of use. In its disclosed

form the attachment comprises a tube which may be generally similar, if desired, to the so-called sunshade that fits over the large end of the telescope of the transit and just tight enough to allow free play. Tangent to a ring around this tube is what I term a straight-edge. Within the tube I provide preferably a pair of prisms which deflect the line of sight from the line of collimation by an angle equal to the mean polar distance of Polaris as hereinafter disclosed. The straight-edge and the prisms are so set with relation to each other that when the straight-edge is lined up with Polaris and β Ursæ Minoris (Polaris being at what I term the "P" end of the straight-edge), and

when the intersection of the cross wires of the transit is at the same time brought onto Polaris, the telescope will then be pointed at the center of the circle described by Polaris, i. e. the Celestial North Pole.

Preferably the prisms are not achromatic. The result is that Polaris, instead of appearing as a point of light, appears as a thin spectrum having a length between 1' and 2' of arc. As the time of year changes, or as the instrument slightly shifts its adjustment from time to time, different parts of the spectrum may be used, the correct part being ascertained from time to time by trial. While obviously my invention is not limited to the use of such types of prisms, and some may prefer achromatic prisms, the adjustments should, for the best results, be made on the yellow of the spectrum, if 20 chromatic prisms are used.

For daylight work, as, for example, in the Forestry Service, the advantage of the spectrum might be outweighed by the disadvantage of not being able to see Polaris so distinctly with chromatic as with achromatic prisms. Obviously my invention is not restricted in its use to either of said types of prisms.

For daylight use, it might prove more practicable to have my invention so graduated that the approximate sidereal time could be set by means of these graduations and a fixed pointer or other mark on the transit rather than by means of lining up an element of my invention on two stars. The presence of such graduations might conversely be used to ascertain the approximate sidereal time when the invention is lined up by means of two stars. My invention in its broadest aspect comprehends such mode of use.

Referring again to the specifically disclosed mode of use involving prisms, it is clearly to be understood that the refraction of the line of sight may, within the scope of my invention, be obtained by any suitable means.

Referring more particularly to the drawing, I have at 1 in Fig. 1 indicated an ordinary surveyor's transit having a telescope 2. Obviously any like or equivalent instrument may be employed. Assuming that the invention is used in connection with a surveyor's transit, such instrument is set up at 55 the station and the plates thereof are set at zero with the transit pointing along the orienting line whose direction is to be determined. Having thus positioned the telescope, the attachment constituting the simplest embodiment of my invention is now placed upon the outer end of the telescope.

This attachment comprises a tube 3 which may desirably be of brass 13 cm. long and 1 mm. thick and of such interior diameter 65 as to give a slip fit over the end of the tele-

scope. For example, this may be 3.7 cm. for most telescopes in use in coast artillery schools. Graduations 40 may be provided on the tube 3 from which, through the fixed indicating line 41 on the telescope, the 70 sidereal time may be read. Desirably and about 120° apart I provide upon the rear end of the cylinder three slits 3' of suitable length. At a suitable distance and desirably about 2 cm. from the end 4 of the tube 3, I 75 provide a flat ring 5, 6. This ring may be formed of one integral piece or as distinct inner and outer members, or if desired the inner member of the ring may be omitted. Desirably this ring is about 3 mm. wide and 80 3 mm. deep, and the inner portion 6 thereof constitutes a stop to prevent the attachment from sliding too far onto the telescope 2. The outer portion 5 of the ring constitutes a support for the so-called straight-edge 7, 85 which, as most clearly shown in Fig. 2, is preferably integral with the portion 5 of the ring. This straight edge is desirably about 15 cm. long and 8 mm. deep, and desirably one end is marked with the letter "P" indicating that such is the Polaris end of the straight edge (thus indicating its preferred mode of use). I may also provide a small knob or pin 8 projecting slightly from the straight-edge to indicate in the 90 darkness which is the "P" end.

Within the front end of the cylinder of the attachment, I position preferably a pair of prisms 9, 10 carried by suitable rings or supports 11, 12 and in connection therewith 100 I provide adjusting means here taking the form of set screws 13, the function of which will be hereinafter more fully set forth.

In the disclosed embodiment of my invention, the pair of prisms are composed of ordinary spectacle glass and are so set that they will deflect the line of sight from the axis of the cylinder by an angular amount of 1° 7' 5", that being taken as the average of the second and third extreme variations 110 in the polar distance of Polaris following the assumed date of adjustment (August 1919). Desirably the prisms are not achromatic, and the result is that Polaris, as stated, instead of appearing as a point of light, appears as a thin spectrum having a length of between 1' and 2' of arc, and the adjustment is desirably made on the yellow of the spectrum.

In Fig. 3, I have indicated the axis of collimation and have also indicated the line of sight which is deflected therefrom by said angular amount of 1° 7' 5". The plane of sight i. e. the plane determined by the line of sight and the refracted line of sight, intersects the "P" end or Polaris end of the straight-edge at an angle of 18° 21.5', that being taken as a similar average with respect to the value of the angle A of the astronomical triangle indicated in Fig. 6. 120 125

The reason for these averages will be hereinafter set forth.

The prisms are secured in place desirably as stated, by means of the inner rings 11, 12, 5 in which they are respectively secured by means of wax or other suitable adhesive used for this purpose. As such connecting means is old and well known in the art, the same is not shown. The rings 11 and 12 are mounted 10 with a close sliding fit in a sleeve 14, in the rear end of which sleeve is a ring 15 which may be locked in position by a set screw 16, while the front end of the sleeve is provided with a flanged ring or cap 17 15 which may be locked in place on the sleeve by a set screw 18.

To permit of proper adjustment of the prisms, the ring 15 is provided with a pair of spaced apart lugs 19-19 which are adapted 20 to receive the adjusting screws 13-13, the adjacent ends of which abut against a lug 20 extending inwardly from the ring 12 so that, by backing out one screw 13 and threading in the other, the ring 12 with its prism 10 may be rotated through a definite angle. The cap 17 is likewise provided with spaced apart lugs 21-21 adapted to receive the adjusting screws 13-13, the adjacent 25 ends of which abut against a lug 22 extending over the ring 11 so that the ring 11 may be turned through an angle as just set forth in regard to ring 12.

Any other suitable means for securing and adjusting the prisms in place may be provided. One alternative method shown in 30 Figs. 7 and 8 is to rotate one prism on the other until the desired degree of refraction is obtained, fastening them together by the use of balsam or other suitable substance. 40 When the prisms have been properly adjusted and secured together they are fastened between the tapered rings 25-25, which rings are secured by suitable means such as the set screws 26-26 within a sleeve 45 27 and mounted in the forward end of the cylinder 28 of the attachment. The sleeve 27 may be secured in position in the cylinder 28 by means of the clamping screw 29. A casing in the form of a ring 30 may be provided to encircle the flange of the sleeve 27 and the forward end of the cylinder 28 and form a guard to preserve the clamping screw from accidental loosening thereof. In this form of device a straight edge is 50 55 formed on the ring 31, which encircles the cylinder 20 and forms an abutment for the rear end of the casing 30.

The telescope is now sighted and the tube 3 is rotated until the straight-edge 7 is lined up with Polaris and β Ursæ Minoris, the observer looking along the outside of the telescope. It will be observed that the straight-edge forms a certain definite angle with the plane of sight, this being equivalent to setting the sideral time. 60

The intersection of the cross wires of the telescope are brought onto Polaris at the same time that the straight-edge is lined up as stated with Polaris and β Ursæ Minoris. The attachment may now be removed. The 70 line of sight is now pointed due north; i. e., at the center of the circle described by Polaris, i. e. the Celestial North Pole, and the azimuth of the reference line can be easily read and determined. It will be found that 75 the angle on the vertical arc is the latitude.

The intersection of the cross hairs or cross lines should be brought on the yellow of the spectrum. As the time of year changes or as the instrument slightly shifts 80 its adjustment from time to time, different parts of the spectrum may be used, the correct part being ascertained from time to time by trial. Desirably a color card is issued with each attachment showing the correct part of the spectrum to use each month. 85

On account of the nearness of Polaris to the pole, its right ascension and polar distance are changing rapidly and extensively.

I have, in describing my invention, referred to the lining up of the straight-edge on Polaris and β Ursæ Minoris. Within the principle and scope of my invention the straight-edge may be lined up with Polaris and some other star, but for reasons herein 90 indicated the best results are obtained by lining up the straight-edge on Polaris and β Ursæ Minoris.

Polaris is the nearest bright star to the Celestial North Pole, β Ursæ Minoris is the 100 brightest star near Polaris, is at a convenient distance for lining upon the straight-edge with Polaris, and changes its position in the sky so slightly as not to necessitate frequent readjustment of my invention. 105

My invention may be employed for determining the true north in the Southern Hemisphere, by causing the transit to point to the Celestial South Pole by means of some two or three bright stars in the Celestial Southern Hemisphere. 110

It will be observed that the straight-edge 7 corresponds to the side A B of the astronomical triangle, and that the angle A is the same as the angle Y indicated in Fig. 2, and is therefore the same value as the angle X indicated in Fig. 2 as $18^\circ 21.5'$. 115

The disclosed embodiment of my invention constitutes a very simple means of north-determination. If adjusted biennially, its extreme error will be well within the limits of precision necessary to heavy artillery orientation, and its average error in practice is negligible and easily reducible to zero. For field artillery the attachment of 120 my invention is sufficiently precise to become the sole method of astronomical north-determination. 125

In determining the true north, the principle of my invention may be used in con- 130

nection with some other star than Polaris, but it is desirable to use the same in connection with Polaris because of the relatively small polar distance thereof.

5 In fact the principle of my invention is applicable to any two stars within convenient distance of either the North or the South Celestial Pole, and the scope of my invention is such as to comprehend such use thereof.

10 In determining the true north, my invention may be employed with circumpolar stars, either north or south, and the straight edge is lined up with two such stars. The 15 telescope or other sighting instrumentality is provided with means for deflecting the line of sight from the line of collimation of said telescope or other instrumentality by an angle equal to the mean polar distance 20 of a circumpolar star. The use of three instead of two stars increases the variability of the accuracy of the instrument. Therefore, preferably I use the same as hereinbefore described, but my invention is not 25 limited to such described use.

30 Having thus described one embodiment of means pertaining to my invention and the best mode known to me for practising the same, I desire it to be understood that although specific terms are employed, they are used in a generic and descriptive sense and not for purposes of limitation, the scope of the invention being set forth in the following claims.

35 Claims:

1. Means for north determination consisting of a mechanical substitute for computation involved in the so-called hour-angle method of north determination, comprising an attachment for a telescope or similar sighting instrumentality, an element carried by the attachment and adapted to be lined up on two stars when the cross hairs of the sighting instrumentality are brought 40 on one of said stars and graduations associated with the said element whereby the sideral time may be determined.

50 2. Means for north determination consisting of a mechanical substitute for the computations involved in the so-called hour angle method of north determination, comprising an attachment for a telescope or similar sighting instrumentality, an element carried by the attachment and adapted to be lined up on two stars when the cross hairs of the sighting instrumentality are brought 55 on one of said stars for the purpose of determining sideral time and means carried by the attachment for deflecting the line of sight of the sighting instrumentality from the line of collimation by an angular amount equal to the north or south polar distance of a given star.

60 3. Means for determining the true north as well as latitude and sideral time, com-

prising a telescope or sighting instrumentality, a part or element associated therewith and adapted to be lined up with circumpolar stars when the cross hairs of the sighting instrumentality are brought on one 70 of said stars, associated means for deflecting the line of sight from the line of collimation of said telescope or instrumentality by an angle equal to the mean polar distance of the star upon which the cross hairs are brought, whereby the line of collimation is caused to point true north or south at an angular elevation equal to the latitude of the place of observation, and graduations and an indicator associated with the element 80 whereby the part or element lined up with the two stars is caused to indicate the sideral time of the observation.

4. Means for determining true north as well as latitude and sideral time, comprising an attachment for a telescope or similar sighting instrumentality, a straight edge carried by the attachment and adapted to be lined up with circumpolar stars when the cross hairs of the sighting instrumentality are brought on one of said stars and associated means for deflecting the line of sight from the line of collimation of the said telescope by an angle equal to the mean polar distance of a certain polar star whereby the line of collimation is forced to point true north or south at an angular elevation equal to the latitude of the place of observation.

5. Means for determination of sideral time comprising an attachment for a telescope and a straight edge carried by the attachment and adapted to be lined up with two circumpolar stars when the cross hairs of the sighting instrumentality are brought on one of said stars, the position of said straight edge indicating the sideral time.

6. Means for north-determination comprising a telescope having a straight edge adapted to be lined up with two heavenly bodies when the cross hairs of the telescope are brought upon one of said bodies and prismatic means for deflecting the line of sight from the line of collimation of the sighting instrumentality with which said means for north-determination is employed 110 by an angle equal to the mean polar distance of one of said heavenly bodies.

7. Means for north-determination comprising a telescope or sighting instrumentality, a part or element associated therewith and adapted to be lined up with two north or south circumpolar stars when the cross hairs of the sighting instrumentality are brought upon one of said stars, and associated means for deflecting the line of sight from the line of collimation of said telescope or instrumentality by an angle equal to the mean polar distance of a north or south circumpolar star.

8. Means for north determination com-

- prising a telescope or sighting instrumentality, a part or element associated therewith and adapted to be lined up with two north or south circumpolar stars when the 5 cross hairs of the sighting instrumentality are brought upon one of said stars, and associated means for deflecting the line of sight from the line of collimation of said telescope or instrumentality by an angle equal 10 to the mean polar distance of one of said stars.
9. Means for north-determination comprising a telescope or other sighting instrumentality having a straight-edge adapted 15 to be lined up with Polaris and another body in the heavens when the cross hairs of the sighting instrumentality are brought upon Polaris and one or more prisms carried by said telescope or instrumentality 20 and adapted to deflect the line of sight from the line of collimation by an angle equal to the mean polar distance of Polaris.
10. Means for north-determination comprising a telescope having a straight-edge 25 tangent to a ring thereof adapted to be lined up with Polaris and another body of the heavens when the cross hairs of the telescope are brought upon Polaris and prismatic means for deflecting the line of sight from 30 the line of collimation of the telescope by an angle equal to the mean polar distance of Polaris.
11. A telescope attachment comprising a ring having a straight edge tangent thereto, 35 and prismatic means adapted to deflect the line of sight from the line of collimation of the telescope to which the attachment is applied by an angle equal to the mean polar distance of Polaris.
- 40 12. Means for north-determination comprising in combination with sighting instrumentality an element or instrumentality adapted to be lined up with Polaris and Ursae Minoris when the cross hairs of the 45 sighting instrumentality are brought upon Polaris and co-acting means to deflect the line of sight from the line of collimation of the sighting instrumentality to which said means for north-determination is applied, 50 by an angle equal to the mean polar distance of Polaris, whereby the sighting instrumentality is pointed at the Celestial North Pole.
13. Means for north-determination comprising a straight-edge adapted to be lined 55 up with two of the heavenly bodies when the cross hairs of the sighting instrumentality with which said means of north determination is employed are brought upon one of said bodies, and means for deflecting the line of sight from the line of collimation of the sighting instrumentality, by an angle equal to the mean polar distance of one of 60 said heavenly bodies.
14. That method of north-determination comprising sighting a telescope or like in- 65 strumentality, lining up an element of the telescope upon Polaris and another body in the heavens so as to obtain one side of the astronomical triangle and simultaneously deflecting the line of sight of the telescope 70 from the line of collimation by an angle equal to the mean polar distance of Polaris whereby the telescope is pointed at the Celestial North Pole.
15. Means for north-determination comprising a telescope having a straight edge exterior to the tube thereof adapted to be lined up on Polaris and another heavenly body when the cross hairs of the telescope are brought upon Polaris and prismatic means 80 for deflecting the line of sight from the line of collimation of the telescope by an angle equal to the mean polar distance of Polaris.
16. That method of north-determination comprising sighting a telescope or like instrumentality, lining up an element of the telescope upon two heavenly bodies so as to obtain one side of the astronomical triangle and simultaneously deflecting the line of sight of the telescope from the line of 85 collimation by an angle equal to the mean polar distance of one of said heavenly bodies, whereby the telescope is pointed at the Celestial North Pole.
17. Means for determining the true north as well as latitude and sideral time, comprising a telescope or sighting instrumentality, a part or element associated therewith and adapted to be lined up with circumpolar stars when the cross hairs of the instrumentality are brought upon one of said stars, associated means for deflecting the line of sight from the line of collimation of said telescope or instrumentality by an 90 angle equal to the mean polar distance of one of said stars, whereby the line of collimation is caused to point true north or south at an angular elevation equal to the latitude of the place of observation, and 95 graduations and an indicator associated with the part or element whereby the part or element lined up with the two stars is caused to indicate the sideral time of the observation, the mean polar distance being taken as an average between the maximum and the 100 minimum polar distance of the star used next succeeding the date of adjustment of the means for north determination.
18. Means for determining the true north as well as latitude and sideral time, comprising a telescope or sighting instrumentality, a part or element associated therewith and adapted to be lined up with circumpolar stars when the cross hairs of the instrumentality are brought upon one of said stars, associated means for deflecting the line of sight from the line of collimation of said telescope or instrumentality by an angle 105 equal to the mean polar distance of one of said stars, whereby the line of collimation 110
- 120
- 125
- 130

- is caused to point true north or south at an angular elevation equal to the latitude of the place of observation, and graduations and an indicator associated with the part or element whereby the part or element lined up with the two stars is caused to indicate the sidereal time of the observation, the angle formed between the line of sight and the line of collimation being taken as an average between the maximum and minimum angle between a great circle joining the two stars lined up and a great circle joining the pole to the star whose polar distance is considered, next succeeding the date of adjustment of the means for north-determination.
19. Means for north-determination comprising a telescope or cylinder having a straight-edge or other part associated therewith and adapted to be lined up with two heavenly bodies when the cross hairs of the telescope or cylinder are brought upon one of said bodies and associated means for deflecting a line of sight from the line of collimation of the telescope or cylinder with which said means for north-determination is employed by an angle equal to the mean polar distance of one of said heavenly bodies, the deflection being radial with respect to the apparent orbit of said heavenly body.
20. Means for north-determination comprising a telescope or cylinder having a straight-edge or other part associated therewith and adapted to be lined up with two north or south circumpolar stars when the cross hairs of the telescope or cylinder are brought upon one of said stars, and associated means for deflecting the line of sight from the line of collimation of the telescope or cylinder with which said means for north-determination is employed by an angle equal to the mean polar distance of one of said stars, the deflection being radial with respect to the apparent orbit of the star whose mean polar distance is selected.
21. Means for north-determination comprising a sighting instrumentality having a straight-edge or other part associated therewith and adapted to be lined up with two heavenly bodies when the cross hairs of the instrumentality are brought upon one of said bodies, and prismatic means for deflecting the line of sight from the line of collimation of the sighting instrumentality with which said means for north-determination is employed by an angle equal to the mean polar distance of one of said heavenly bodies, the deflection being radial with respect to the apparent orbit of said heavenly body.
22. Means for north-determination comprising a sighting instrumentality having a straight-edge or other part associated therewith and adapted to be lined up with two north or south circumpolar stars when the cross hairs of the instrumentality are

brought upon one of said stars, and prismatic means for deflecting the line of sight from the line of collimation of the sighting instrumentality with which said means for north-determination is employed by an angle equal to the mean polar distance of one of said stars, the deflection being radial with respect to the apparent orbit of the star whose mean polar distance is selected. 70

23. Means for north-determination comprising a telescope having a straight-edge tangent to a ring thereof and adapted to be lined up with Polaris and another heavenly body when the cross hairs of the telescope are brought upon Polaris and prismatic means for deflecting the line of sight from the line of collimation of the telescope by an angle equal to the mean polar distance of Polaris, the deflection being radial with respect to the apparent orbit of Polaris. 75

24. A telescope attachment comprising a ring having a straight-edge tangent thereto, and prismatic means adapted to deflect the line of sight from the line of collimation of the telescope to which the attachment is applied by an angle equal to the mean polar distance of Polaris, the deflection being radial with respect to the apparent orbit of Polaris. 80

25. Means for north-determination comprising a telescope or sighting instrumentality, a part or element associated therewith and adapted to be lined up with two heavenly bodies when the cross hairs of the telescope or instrumentality are brought upon one of said bodies, and associated means for deflecting the line of sight from the line of collimation of said telescope or like instrument by an angle equal to the mean polar distance of a circumpolar star. 100

26. Means for north-determination comprising a telescope or other sighting instrumentality having a straight-edge adapted to be lined up with two north or south circumpolar stars when the cross hairs of the telescope or sighting instrumentality are brought upon one of said stars, and one or more prisms adapted to be carried by said telescope or instrumentality and adapted to deflect the line of sight from the line of collimation by an angle equal to the mean polar distance of a circumpolar star. 110

27. Means for north-determination comprising a telescope or cylinder having a straight-edge tangent to a ring thereof and adapted to be lined up with heavenly bodies when the cross hairs of the telescope or cylinder are brought upon one of said bodies, and prismatic means for deflecting the line of sight from the line of collimation of the telescope by an angle equal to the mean polar distance of a heavenly body. 120

28. A telescope attachment comprising a ring having a straight-edge tangent thereto, and prismatic means adapted to deflect the 125

line of sight from the line of collimation of the telescope to which the attachment is applied by an angle equal to the mean polar distance of a heavenly body.

- 5 29. Means for north determination comprising a telescope or sighting instrumentality, a part or element associated therewith and adapted to be lined-up with two north or south circumpolar stars, when the cross hairs of the sighting instrumentality are brought upon one of said stars and associated means for deflecting the line of sight from the line of collimation of said telescope or instrumentality by an angle equal 10 to the main polar distance of one of said stars, the angle between the plane of sight and the lined-up part or element being taken as the average between the maximum and the minimum values (next succeeding 15 the date of adjustment of the means for north determination) of the angle at the sighted star subtended by the Celestial North Pole and the other star.
30. Means for north determination comprising a telescope or sighting instrumentality, a part or element associated therewith and adapted to be lined-up with two north or south circumpolar stars, when the cross hairs of the sighting instrumentality are brought upon one of said stars and associated means for deflecting the line of sight from the line of collimation of said telescope or instrumentality by an angle equal to main 20 polar distance of one of said stars, the lining up not requiring any particular position 25 of the eye of the observer.

31. Means for north determination comprising a telescope or sighting instrumentality, a part or element associated therewith and adapted to be lined-up with two north 40 or south circumpolar stars, when the cross hairs of the sighting instrumentality are brought upon one of said stars and associated means for deflecting the line of sight from the line of collimation of said telescope or instrumentality by an angle equal to the main polar distance of one of said stars, the angle between the plane of sight and the lined-up part or element being taken as the 45 mean value of the angle at the sighted star subtended by the Celestial North Pole and the other star.

32. Means for north determination comprising a telescope or sighting instrumentality, a part or element associated therewith 50 and adapted to be lined-up with two north or south circumpolar stars, when the cross hairs of the sighting instrumentality are brought upon one of said stars and associated means for deflecting the line of sight from the line of collimation of said telescope or instrumentality by an angle equal to the main polar distance of one of said stars, the angle between the plane of sight and the lined-up part or element being taken as the 55 mean value of the angle at the sighted star subtended by the Celestial North Pole and the other star, said angle not being adjustable by the observer.

In testimony whereof, I have signed my 70 name to this specification.

ROGER SHERMAN HOAR.
